BUCKLE

Aleis A. Ritter, Racine, Wis., assignor to Hartmann Trunk Company, Racine, Wis., a corporation of Wisconsin

Application October 8, 1942, Serial No. 461,354

8 Claims. (Cl. 24—207)

This invention relates to improvements in buckles.

Buckles for securing complementary strap sections together are customarily formed of metal. Due to the present scarcity of metal for civilian commodities, it is now highly desirable to eliminate the use of metal wherever possible, and it is therefore, a primary object of the present invention to provide a non-metallic strap buckle of simple and efficient construction.

A further object of the invention is to provide non-metallic buckle mechanism for complementary strap sections wherein one of the strap sections carries adjustable buckle elements and the other strap section is formed with a series of spaced apertures and is adapted to be adjustably and selectively engaged by the buckle elements.

A further object of the invention is to provide non-metallic buckle mechanism for complementary strap sections to which, when the strap sections are secured together by the buckle mechanism, a small padlock may be readily applied to prevent unauthorized release of the buckle mechanism.

A further object of the invention is to provide a leather buckle structure applicable to the retaining straps of a trunk or hand luggage case, blending with the exterior materials of the trunk or luggage case and presenting a unique, attractive and rugged appearance.

A further object of the invention is to provide a complementary strap section buckle which may be easily and quickly manipulated, which provides a very secure and effective fastening, which is strong and durable, which is inexpensive to manufacture, and which is well adapted for the purposes set forth.

With the above and other objects in view the invention consists of the improved buckle, and its parts and combinations as set forth in the claims, and all equivalents thereof.

In the accompanying drawings in which the same reference characters indicate the same parts in all of the views:

Fig. 1 is a perspective view of a hand luggage bag wherein the complementary straps for the securing of the bag section closure flaps are releasably engaged by the improved buckles;

Fig. 2 is an enlarged, fragmentary, detail view of the side of the closed luggage bag showing the securing straps engaged by the buckle;

Fig. 3 is a similar view only showing the double slide loop member of the buckle structure in a position to permit release of the buckle tongue;

Fig. 4 is a fragmentary vertical sectional view

taken on line 4—4 of Fig. 2, and on a larger scale, only with the padlock removed;

Fig. 5 is an enlarged, fragmentary, vertical sectional view of the showing in Fig. 3 only with the buckle tongue turned to permit its withdrawal from a strap aperture;

Fig. 6 is an enlarged, fragmentary, vertical sectional view showing the complementary strap sections separated and disengaged through the withdrawal of the buckle tongue from a strap aperture;

Fig. 7 is a transverse sectional view taken on line 7—7 of Fig. 2; and

Fig. 8 is a top view of another form of hand luggage case wherein the complementary securing straps for the case sections are releasably engaged by the improved buckles.

Referring now more particularly to the drawings, it will appear that in Figs. 1 to 7, inclusive, the improved buckle structure is, by way of illustration, shown applied to a soft-sided hand luggage bag comprising a compartmental body section 10 having flexible side walls 11, there being open upper ends to the compartments of the body section adapted to be closed and covered by flexible flaps 12. These flaps have their inner edge portions secured in meeting relationship along the top longitudinal median of the body section 10. These flaps 12 are adapted to flexibly drape over and cover the open ends of the compartments of the body section 10 and to have their free edge portions extended over outer side wall portions 11 of the bag. When the bag is packed for transportation purposes, the flaps 12 are retained in the closing positions illustrated in Fig. 1 by means of sets of complementary straps 13 and 14 respectively. The straps 13 may have their inner ends secured within the seam formed at the securement of the inner edges of the cover flaps 12. The straps 14 may have their inner ends secured along the bottom longitudinal median of the bag. The straps 13 and 14 are all slidably extended through guides 15 properly positioned on and secured to portions of the flaps 12 and side walls 11. For the purpose of releasably retaining the closure flaps 12 in their covering positions, the free ends of the complementary straps 13 and 14 are brought together in overlapping relationship along side wall portions of the bag, as shown, and are releasably secured together in proper adjusted positions by means of the improved buckles, forming the subject of this invention.

The improved buckle mechanism shown in detail in Figs. 2 to 7 inclusive includes an elongated

gated leather tongue 16 turnably connected at one end to an outer face portion of a free end of a strap 14, being that portion of said strap which is adapted to be overlapped by a depending free end portion of a complementary strap 13. The tongue 16 is considerably narrower than the strap 14 upon which it is mounted. The tongue is formed of an elongated flexible leather strip doubled over or looped upon itself with the free ends thereof in superimposed relation and turnably mounted on the extended shank portion of a rivet 17 which is secured in the strap 14. The doubled or two-ply tongue 16 is swingable upon the shank of the rivet 17, and the superimposed ends of the tongue mounted on the rivet shank are rounded, for the purpose hereinafter to be set forth. The closed or looped free end of the tongue is utilized for the reception of the locking bar 18 of a small padlock 19, as will hereinafter appear. The free end portion of the overlapping complementary strap 13 is provided with a series of spaced apart oval or eccentrically shaped openings 20.

To releasably engage the overlapping free end portions of a pair of complementary straps 13 and 14 through the improved buckle mechanism, the straps are first brought into overlapping relationship, and if the same are applied to a luggage bag, as in Fig. 1, the straps serve to hold in covering relationship the flaps 12. The two-ply leather tongue 16 should be turned on the rivet 17 so as to extend longitudinally beyond the free end of the strap 14, in the manner shown in Fig. 6. Then the free end of the tongue 16 is passed entirely through a selected opening 20 in the overlapping strap 13, whereupon the engaged portion of the strap 13, in the region of the opening 20 through which the tongue has passed, is snapped over the shoulder formed at the rounded inner end of the tongue so as to lodge on the rivet shank inwardly of the secured end of the tongue. Thereafter, when the tongue 16 is swung through an arc of 180° to the position of Fig. 4, the tongue will overlie the secured portion of the strap 13 to hold it in firm engagement with the strap 14.

There is freely slidably mounted on the strap 14 a double slide loop member 21. This double slide loop member has an inner large loop portion embracing the strap 14 and superimposed on the large loop portion is a smaller loop portion 21'. When the double slide loop is moved along the strap 14 toward that portion which is overlapped by the strap 13, the inner large loop will slide over and confine the extended portion of the strap 13, easily moving onto the same by virtue of the fact that the free extremity of the strap 13 is tapered, as shown. Continued movement of the double slide loop in the same direction will permit the extended portion of the tongue 16 to be passed through the small superimposed loop portion 21', resulting in the arrangement shown in Figs. 1, 2, and 4, wherein this position of the slide loop will effectively prevent any swinging or turning movement of the buckle tongue 16, so that the overlapping strap portions are effectively secured together in adjusted relationship. When it is desired to lock the bag or container to which the straps are applied, against unauthorized opening, the bar portion of a small padlock 19 may be passed through the closed looped end of the tongue 16 and locked in position as shown in Figs. 1 and 2.

When the buckle tongue 16 is in the engaged securing position of Figs. 1 to 4 inclusive, stock

5 of the tongue adjacent the secured end of the tongue and beyond the lip of the opening 20 engaged by the rivet 17 firmly engages the overlapping strap 13 and prevents it from slipping outwardly over the rivet and the shouldered end of the tongue. The buckle mechanism may be quickly released and the straps 13 and 14 separated through reversal of the operations described.

10 The improved buckle is completely devoid of metal except for the rivet 17 which, if necessary, might be formed of wood, fiber, plastic, or other non-metallic material.

A slight modification of the invention is illustrated in Fig. 8 wherein the buckle mechanism is applied to complementary strap sections 13' and 14' which in their application need not be adjustably secured together. In the modified exemplification the complementary straps 13' and 14' 15 are secured to rigid walled sections 10a and 10b of a box-like hand luggage case. When the complementary case sections 10a and 10b are in closed relationship, the overlapping strap sections 13' and 14' always meet in the same relationship and hence the overlapping free portions 20 of the straps 13' are provided with but single apertures through which the tongues 16 are extended when the buckles are to be engaged. In other respects the arrangement is as described in 25 connection with the principal form of the invention and double slide loops are engaged over the straps 13' and tongues 16 for purposes of secu- 30 rement.

From the foregoing description it will be seen 35 that the improved non-metallic buckle mechanism is susceptible of application wherever it is desired to releasably secure together the meeting ends of a pair of securing straps. The buckle is 40 of simple and novel construction and is well adapted for the purposes set forth.

What is claimed as the invention is:

1. In combination with a pair of strap ends brought into overlapping relationship, one of the strap ends having an aperture therein, a buckle, comprising a flexible tongue having one end portion turnably mounted on the other strap end, the tongue being insertable through the aperture in the first-mentioned strap end, and means movably carried by a strap end and engageable with 45 the tongue for retaining the same in said inserted condition.

2. In combination with first and second strap ends brought into overlapping relationship, the first strap end having an aperture therein, a buckle, comprising a flexible tongue having its inner end portion turnably mounted on the second strap end and extendable through the first strap end aperture, and a slide fastener slidably mounted on the second strap end and movable onto the first strap end and the tongue to releasably retain both of the same in connected relationships.

3. In combination with first and second strap ends brought into overlapping relationship, the first strap end having an aperture therein, a buckle, comprising a flexible, elongated tongue of less width than the second strap end and having its inner end turnably mounted on said second strap end and extended bodily through the first strap end aperture, and a double slide loop mounted on the second strap end and adjustably movable therealong to confiningly, releasably engage both the first strap end and the tongue.

4. In combination with first and second strap ends brought into overlapping relationship, the

first strap end having an aperture therein, a buckle, comprising a flexible, elongated tongue of less width than the second strap end and having its inner end turnably mounted on said second strap end and extended bodily through the first strap end aperture, the free end portion of said tongue being in the form of a closed loop, a double slide member mounted on the second strap end and adjustably movable therealong onto and beyond the looped end of the tongue to confiningly, releasably engage both the first strap end and the tongue to secure the strap ends and tongue in superimposed relationship, and a lock detachably engaging the looped end of the tongue to prevent undesired removal of the slide member from said tongue.

5. In combination with first and second strap ends brought into overlapping relationship, the first strap end having a series of spaced apertures therein, a buckle, comprising a flexible, elongated tongue of less width than the second strap end and having its inner end turnably mounted on said second strap end and extended bodily through a selected aperture in the first strap end, and a double slide loop mounted on the second strap end and adjustably movable therealong onto the first strap end and onto the tongue to confiningly, releasably engage said first strap end and the tongue to hold the same in superimposed relationship relative to the second strap end.

6. A fastening device, comprising a pair of complementary strap sections, the first strap section having an opening therein, a stud projecting from the second strap section, and a flexible tongue having one end portion turnably mounted on said stud, the tongue, in one turned position being bodily insertable through the first strap opening, and in another turned position overlying

10 the apertured end of the first strap section and holding it tightly against the second strap section.

15 7. A fastening device, comprising a pair of complementary strap sections, the first strap section having an opening therein, a stud projecting from the second strap section and having a shoulder, and an elongated flexible, narrow tongue having its inner end portion turnably mounted on said stud, one turned position of the tongue permitting entrance of the same through said first strap opening and relative movement of said strap and tongue for engagement of said strap opening over the stud shoulder, and another turned position causing the tongue to overlie the apertured engaged end of the first strap section with both strap sections in overlapping relationship and preventing removal of the first strap section opening from the stud shoulder.

20 8. A fastening device, comprising a pair of complementary strap sections, the first strap section having a series of spaced apertures therein, a stud projecting from the second strap section, an elongated, flexible, narrow tongue having its inner end portion turnably mounted on said stud and forming a shoulder, said tongue, when in one turned position, being bodily slideable through a selected aperture in said first strap section with said first strap section aperture forced over the tongue shoulder and stud, the tongue in another turned position having its shoulder overlying stock of the first strap section adjacent said aperture to prevent movement of the first strap section along the tongue, and a slide loop mounted on the second strap section and movable therealong to releasably embrace and hold in superimposed relation both strap sections and the tongue.

ALOIS A. RITTER.
